CUFF LINK

Charles H. Hone, Millburn, N. J., assignor, by
mesne assignments, to Swank Products, Inc.,
a corporation of Delaware

Application August 23, 1934, Serial No. 741,065

5 Claims. (Cl. 24—102)

This invention relates to cuff links and the object of the invention is to simplify former constructions and at the same time provide a structure which will be stronger, more durable and more readily manipulated than prior constructions, and which may be expeditiously and easily inserted and removed from the most stiffly starched cuffs.

Cuff links, as heretofore made, generally embody a link member or tie at the opposite ends of which are secured appropriate heads, one or both of which are generally pivotal with respect to the link element, so as to permit the structure to be more readily associated with a cuff. In the majority of structures heretofore employed, however, there are projections incident to the pivotal connections between the movable head and the link element which are apt to catch and tear the stitches which enter into the buttonhole structure. Furthermore, it is common to pivotally connect the movable head laterally or to one side of the link.

The present invention differs from these structures in that the link element is bifurcated to provide spaced apart arms between which the movable head is mounted for pivotal movement, the arrangement being such that there are no sharp or irregular projections and when pressure is applied to the movable head to force it through a buttonhole, the pressure is equally distributed throughout the pivotal connection in such manner as to place no undue bending strains thereon.

A further object of the invention is to so constitute the pivotal connection between the link element and the movable head that it is adapted to be normally held in either of its two distinct positions. In other words, it may be locked in this position for insertion into or removal from a cuff and it can be similarly locked in its normal closed position after introduction into the cuff, whereby it cannot be inadvertently displaced or lost.

The invention further provides for improvements in the locking means referred to in order to give greater strength and durability than heretofore found in cuff links.

Features of the invention, other than those adverted to, will be apparent from the hereinafter detailed description and claims, when read in conjunction with the accompanying drawing.

The accompanying drawing illustrates different practical embodiments of the invention, but the constructions therein shown are to be under-

stood as illustrative, only, and not as defining the limits of the invention.

Figure 1 is a perspective view showing a cuff link embodying the present invention.

Figure 2 is a central section through the movable head of the structure shown in Figure 1 and illustrating a fragmentary part of the link element.

Figures 3 and 4 are similar views of modified forms of construction.

Figure 5 is a section on the line 5—5 of Figure 3.

In referring to the drawing, 1 designates generally a link element of the structure. This link element is preferably bifurcated at both ends, 15 so as to provide a relatively long slot 2, at one end, and a relatively short slot 3 at the other end. Between the arms 4 at the opposite sides of the slot 3 is introduced a stationary head 5 of the cuff link and this head is preferably soldered or otherwise permanently secured rigidly in position with respect to the link element 1.

Between the arms 6 at the opposite sides of the slot 2 is pivotally secured the movable head 7. This head is shown in the form of an elongated 25 tubular section provided centrally with oppositely disposed circular holes 8 in its side walls and through which holes a pivot pin 9 is adapted to be passed. This pivot pin 9 is preferably in the form of a square bar, the opposite ends 30 of which are anchored in correspondingly shaped holes in the arms 6 with the intermediate portion of the pin 9 extending through the hollow center of the head 7. The circular holes 8 have a diameter substantially equal to the diagonal 35 dimension of the pin 9, so as to permit rotary movement of the head 7 about the pin and at the same time substantially centralize the head with respect to the pin, so that said rotation will be substantially coaxial with respect to the pin. 40 If desired, that portion of the pin on which the head 7 rotates may be made circular, so as to give a better bearing, but I find in practice that this is not necessary. The head 7 is thus mounted to rotate on the pin 9 and the slot 2 is made 45 long enough to permit the ends of the head 7 to clear the blind end of the slot during this operation.

The interior structure of the head may vary, as shown in Figures 2—5. In the structure of Figure 2, the opposite ends of the head 7 are shown as closed by jewels 10 and directly adjacent the opposite sides of the pin 9 are positioned plungers 11 which preferably substantially conform to the cross section of the head 7 and between the jewels 55

10 and the plungers 11 are positioned helical springs 12. In practice the jewels may be secured in place with sufficient firmness to withstand the reaction of the springs, although in practice I 5 preferably carry this strain upon angles or rings 13 soldered or otherwise firmly secured in place. The springs are inserted under sufficient tension to force the plungers firmly against the polygonal section of the pin 9 for the purpose of locking the head 7 against inadvertent rotation 10 with respect to the pin and consequently with respect to the link element 1. Inasmuch as the section of the pin 9 is rectangular, it follows that the head may be locked either in its closed position, as shown in Figure 1, or in a position at 15 right angles to the position of Figure 1 with the head 7 substantially aligned with respect to the link 1. When in this latter position, the device may be readily associated with a cuff by forcing the head longitudinally through the buttonholes thereof. This operation is facilitated by making the jewels 10 of tapering configuration. After 20 the head 7 has been passed through the buttonholes, it may be manually rotated against the tension of the springs 12 into the position shown in Figure 1 to close the link and thus maintain it in position. When in this latter position, the springs 12 exert sufficient pressure through the plungers 11 upon the flat opposite sides of the 25 pin 9 to preclude inadvertent pivotal movement of the head 7.

I have referred to the use of jewels 10 at the opposite ends of the head 7, but, if desired, these 30 may be omitted and the ends of the head closed in any appropriate way and shaped in any desired form. Both of the heads 5 and 7 are also shown as of the same substantially rectangular prismatic shape, although they may be of other shapes if so desired, and may be made of different 35 shapes from one another. However, the form shown is highly satisfactory. Moreover, the link element 1 is shown as projecting somewhat beyond the heads in Figure 1, and the heads are shaped at their centers to conform to the extended portions of the link 1, although the ends 40 of the link may be cut off flush with the face of the heads and the extensions on the heads omitted if desired.

Figure 3 illustrates a modified form of construction. Here, instead of employing two helical springs bearing against the opposite lateral edges 45 of the pin 9, I employ a single double armed leaf spring 14, so formed that its arms 15 and 16 bear against the opposite sides of the pin and are bowed to engage therewith under considerable 50 pressure which is amply sufficient to lock the head 7 in either of its operative positions.

Figure 5 shows a cross section of the structure of Figure 3 and illustrates the manner in which 55 the pin 9 is firmly secured to the arms 6 of the link element with the arms 15 and 16 of leaf spring 14 bearing against the opposite flat faces of the pin to lock the head 7 in position.

Figure 4 illustrates a further modified form of construction. Here the head 7 is rotatable on the 60 pin 9 as before, but is normally locked in position by means of two leaf springs 17 and 18, the free ends of which engage with the pin 9, while the opposite ends of which are firmly secured to the 65 interior of the wall of the head 7 as by rivets 19.

In Figures 3 and 4, leaf spring arrangements 70 are shown, but I prefer in practice to use the structure of Figure 2 embodying the two helical springs 12 for the reason that these springs will 75 retain their resiliency much longer than a leaf

spring and furthermore do not subject the parts to as much wear as is the case with the leaf spring construction.

The construction of Figure 3, however, has the advantage that the whole spring assembly 5 may be handled as a unit and at the same time the securing of the arms 15 and 16 together by the intermediate cross piece 20 not only facilitates assembly, but also serves to hold both arms of the spring in proper cooperative relation intermediate the ends of the head and thereby relieve the jewels from outward pressure.

In the structures which I have described, the device has been defined in each instance as having a fixed head and a movable head, but, if 15 desired, both heads may be made pivotal, without departing from this invention.

The foregoing detailed description sets forth the invention in its preferred practical and illustrative forms, but the invention is to be understood 20 as fully commensurate with the appended claims.

Having thus fully described the invention, what I claim as new and desire to secure by Letters Patent is:

1. In an assembly of the character described, a link provided at its opposite ends with heads, at least one of which is pivotal with respect to the link, said link being bifurcated to receive the movable head, a pin extending across the bifurcated end of the link and through the movable head and having a polygonal cross section within the confines of said head, and a pair of plungers positioned within the heads at the opposite sides of said pin, and a spring interposed between 35 each plunger and the corresponding end of the head and exerting sufficient tension upon the plungers to preclude inadvertent rotation of the head.

2. In a cuff link, an elongated body member 40 comprising two spaced arms at one end thereof, a head secured to the other end thereof, an angular bar secured between said spaced arms, a tubular head having aligned openings for pivotal mounting on said angular bar, a U-shaped spring 45 in said tubular head for engaging said angular bar to releasably lock said tubular head in selected positions parallel to said body member and at right angles thereto, said U-shaped spring comprising arcuate spring tongues contacting 50 said angular bar on opposite sides thereof and contacting the walls of said tubular head at its ends, and closure members for the ends of said tubular head.

3. In a cuff link, an elongated body member 55 comprising two spaced arms at one end thereof, a head secured to the other end thereof, an individual angular bar extending between and mounted on each of said spaced arms and presenting faces one in line with the body and one 60 at right angles thereto, a tubular head having aligned openings pivotally mounted on said angular bar, spring means concealed in said tubular head for engaging one of the surfaces of said angular bar to releasably lock said tubular head 65 in selected positions in line with said body member or at right angles thereto, and closure means for the ends of said tubular head.

4. In a cuff link, an elongated body member comprising two spaced arms at one end thereof, 70 a head secured to the other end thereof, an individual angular bar extending between and mounted on each of said spaced arms and presenting faces one in line with the body and one 75 at right angles thereto, a tubular head having 95

aligned openings pivotally mounted on said angular bar, spring means concealed in said tubular head for engaging one of the surfaces of said angular bar to releasably lock said tubular head in selected positions in line with said body member or at right angles thereto, said spring means comprising arcuate leaf spring tongues contacting said angular bar on opposite sides thereof and contacting the walls of said tubular head at their ends, and closure members for the ends of said tubular head.

5. In a cuff link, an elongated body member comprising a head secured at one end thereof,

two spaced arms at the other end thereof, a tubular head of elongated shape with a central portion enlarged in diameter, an angular pivot bar extending through the enlarged portion of said tubular head and into the spaced arms to pivotally mount the head at such location in the arms that when the head is at right angles to the arms the enlarged portion is substantially flush with the ends of said arms, and resilient means engaging the faces of the bar for retaining the head 5 in different positions aligned with or at right angles to the arms.
